FLYING-MACHINE

965,452.

Specification of Letters Patent. Patented July 26, 1910.

Application filed February 5, 1909. Serial No. 478,242.

To all whom it may concern:

Be it known that I, FRED L. GOULD, a citizen of the United States, and a resident of Reno, in the county of Washoe and State of Nevada, have invented a new and Improved Flying-Machine, of which the following is a full, clear, and exact description.

This invention relates to flying machines of a type that are heavier than air, and which are adapted by contained mechanism to rise upwardly to a desired height, traverse the air in any direction and if desired, return to the starting point on the surface of the earth.

The primary object of my invention is to provide novel details of construction for a flying machine of the type indicated, that embody a parachute automatically convertible into a multiple lifting aeroplane and the reverse, by a suitable adjustment of the motive agent; and a further object is to provide novel means that adapt the multiple aeroplane mechanism to direct the course of the machine in any desired direction.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is an axial vertical sectional view, substantially on the line 1-1 in Fig. 2; Fig. 2 is a broken plan view, taken substantially on the line 2-2 in Fig. 1; Fig. 3 is a transverse sectional view of details, 40 showing the adjustment of one of a plurality of aeroplanes by full and dotted lines, and taken substantially on the line 3-3 in Fig. 2; Fig. 4 is an enlarged side view of a torsion spring, and parts of the apparatus connected thereto; Fig. 5 is a partly sectional plan view of details, substantially upon the line 5-5 in Fig. 1; and Fig. 6 is a detached plan view of one of a plurality of aeroplanes that are details of the invention.

In the drawings that illustrate the improved flying machine, 10, 11, indicate two

hollow masts, the mast 10 having greater length than the mast 11 and being slidably fitted in the latter, as appears in Fig. 1 for convenience in assembling.

A skeleton frame 12, circular in form peripherally considered and having parallel upper and lower sides, is furnished with a step or socket box *a* at the center of the lower side that receives a journal end *b* that is formed on the lower extremity of the mast 10. A suitable motor 13 is placed in the frame 12 at one side of the shaft 10 and from one side of the motor a driving shaft *c* is extended whereon a bevel gear *c'* is secured. Below the gear *c'*, a bevel pinion *d* is mounted upon the mast 10 and secured thereto, said pinion meshing with the lower side of the bevel gear *c'*.

Upon the lower extremity of the hollow shaft 11, a bevel pinion *e* having an equal diameter with the pinion *d*, is formed or secured and meshes with the bevel gear *c'* directly above the pinion *d*. On the hollow shaft 11 at a suitable point above the pinion *e*, a sleeve 14 is loosely mounted, said sleeve being secured to the upper side of the motor frame 12, and between the lower end of the sleeve 14 and the shaft 11, a ball bearing *f* is placed.

A circular car frame 15, having an open top and a skeleton framed lower side *g*, is supported concentric with the motor frame 12 by means that will now be described. A circular supplementary frame 15^a, that is a portion of the car frame 15, is erected concentric with and near the side wall of the motor frame 12 and extending above it. Upon the inner ends of a plurality of inwardly-extending arms *h* that project from the upper ends of the standards forming the supplementary frame 15, an eccentric strap 16, in the form of a ring having a continuous groove in its inner wall, is secured. An eccentric body 17 in disk form, is provided with a tongue or rib *i* on its periphery, that is loosely fitted into the groove in the eccentric strap 16, and at a suitable point eccentric to the tongue *i*, a circular opening 100 is formed in the eccentric body for the reception of the upper end of the sleeve 14, whereon said eccentric body is mounted and secured. A hand wheel 18 is attached upon

the eccentric body 17 by means of the spider arms *k* that project from the rim of said wheel inwardly and lap on said body to which said arms are secured.

- 5 On the bottom wall of the car frame 15, a base plate 19 is secured at its center, said base plate having a groove *m* in its upper surface that has similar eccentricity with that of the body 17, and from the lower 10 side of the socket box *a* a stud *m'* projects downward and seats in the groove *m*.

In the relative position of the parts as shown in Figs. 1 and 5, the eccentric body 17 is adjusted so as to dispose said body at 15 the center of the motor supporting frame, and also of the car frame, thus disposing the masts 10, 11, eccentric to these frames.

It will be apparent that by turning the hand wheel 18, the rotatable movement of 20 the eccentric body 17 will change the position of the masts 10, 11, with relation to the motor-supporting frame and the car frame.

The means for effecting an elevation of the apparatus embodies two similar structures, each consisting of the following details: At a suitable distance above the motor frame 12, a radial flange 19 is secured upon the hollow mast 11, said flange having a circular edge and sufficient area for its 25 service that will presently be explained. A collar *n* is formed or secured on the upper end of the hollow mast 11, above which the mast 10 extends, and on said mast 10, a thimble 20 is loosely mounted. A coiled spring 21, of suitable dimensions and tensional strength, is mounted upon the mast 10 between the collar *n* and the thimble 20, perforated and flattened eyes *o*, *o*, formed on the ends of the spring coil 21 being 30 lapped upon and secured to said collar and thimble respectively, as is clearly shown in Fig. 4. Upon the thimble 20, a parachute 22, of considerable area, is secured, said 35 parachute being formed of thin plate metal, circular on its edge and having a concavo-convex shaped body, the concave side thereof being disposed lowermost. The parachute is provided at its center with a 40 depending collar *p* that is mounted and secured upon the thimble 20 and thus is secured in a plane at right angles to the axis of the masts 10, 11, as shown in Fig. 1. At 45 equally spaced intervals, a series of apertures *q* is formed in the thin body of the parachute 22, these similar openings being positioned at an equal distance from and 50 near the periphery of the parachute body, as is clearly shown in Fig. 2. The side edges of each opening *q* converge somewhat 55 from their outer ends toward the inner transverse end wall thereof, and as shown in Fig. 2, the end walls or edges of the openings *q* are segments of two concentric circles, as appears in full lines at the right in

said view, the remaining apertures *q* being 65 represented in part by broken lines.

A series of thin plate metal aeroplanes 23 equal in number with the series of apertures *q* are provided. These planes have a marginal form that corresponds with that of 70 said apertures, but are slightly greater in area, thus affording an overlapping edge portion for each plane 23 when imposed upon the parachute body over the openings *q* respectively. As shown for one plane 23 in 75 Fig. 6, each aeroplane is formed with a short slot *r* in each end thereof at the transverse center. In the end walls or edges of each aperture or opening *q* at their centers, a short slot *r'* is formed and thus disposed oppositely in each opening, said slots appearing in the edges of one opening *q* at the right in Fig. 2, and it is to be understood that all the openings have similar slots.

To place the aeroplanes 23 in position, 85 each one is by slightly bending it, readily inserted in a respective aperture *q*, and at each end the aeroplane and parachute are loosely interlocked by engaging said ends at the respective slots *r*, *r'*, with the corresponding transverse edges at the ends of the openings *q*, this engagement being effected by straightening the aeroplanes after they are inserted and properly positioned in the openings they are to occupy. 95

It will be seen that by the loosely interlocked engagement of each aeroplane 23 with an opening or aperture *q*, said aeroplanes are all adapted to receive rocking adjustment on the parachute body 22, so as to open partially 100 or completely close the openings *q*.

From the described construction and arrangement of the parts, it will be obvious that the side edge portion of each aeroplane 23 will when in closed adjustment, lap over 105 the edge of a corresponding opening *q*, one-half of said edge portion seating on the upper or convex side of the parachute body, and the other half portion of said edge having a similar engagement with the concave 110 or lower side of said parachute.

From the side edges of each aeroplane 23, a plurality of wires 24 or like connections, are extended toward the radial flange 19 and secured thereon by attaching the grouped 115 ends of said wires thereto, these groups of wires or the like being so spaced apart on the radial flange 19 and having such length respectively, that when the spring 21 is fully expanded the aeroplanes 23 will be folded 120 upon the parachute and virtually render its wall imperforate.

A radial flange 25, similar to the radial flange 19, is placed on and secured to the mast 10 immediately above the parachute 22, 125 and as shown in Fig. 1 a ball bearing 25^a is introduced between the thimble 20 and the lower side of the flange 25. At a distance

from the flange 25, equal with the distance that intervenes between the flange 19 and parachute 22, a similar parachute 26 is mounted upon the upper end of the mast 10, 5 said parachute having a depending thimble *s* secured thereto at its center.

A collar *s'* is formed or secured on the upper end of the mast 10, and between said collar and the lower end of the thimble *s* a 10 spiral spring 27 is introduced that is similar to the spring 21 and is secured by its ends respectively upon said collar and thimble, thus adapting it to serve as a torsion spring and also as an expansible spring.

15. The parachute body 26 which is of thin plate metal, has an equal area to that of the parachute 22, is of a like curvature and is formed with apertures equal in number to those provided in the parachute 22 and of a 20 like marginal form.

Aeroplanes 28, equal in number to and having the same form as the aeroplanes 23, are hinged in a like manner to that of the aeroplanes 23, so as to rock in the apertures 25 in the parachute 26. Each aeroplane 28 is connected at its side edges by wires 29 with the radial flange 25, and when the coiled spring 27 is fully expanded, the aeroplanes 28 will be drawn by said wires into flat 30 contact with the surface of the parachute body 26.

The car frame 15 is preferably covered with strong wire netting 15^b that also covers the bottom of the frame 12, and upon the 35 car frame at its center, elliptical springs 15^c are secured where said springs cross at their centers. Between the ends of the elliptical plate springs 15^c and the bottom wall of the car 15, strong coiled springs 15^d are inserted 40 and secured, these coiled springs and plate springs affording a resilient base for the entire flying machine while resting on the ground, and also serving to cushion its impact thereon when descending after an as- 45 cension.

In operation, assuming that the flying machine is in upright position on a solid base that may be the surface of the earth, and all parts in the relative positions indicated in 50 Fig. 1, the aeroplanes 23 and 28 being nearly closed, the motor 13 is started, thus rotating the bevel gear *c'*. The pinions *d* and *e* are simultaneously rotated by the bevel gear *c'*, rotating the masts 10, 11, in opposite directions at an equal speed. When the rate of 55 speed of the masts has attained a sufficient degree and the parachutes 22 and 26 are correspondingly rotated, their resistance to rotation will cause the torsion springs 21 and 27 to twist and correspondingly shorten the distance between the radial flanges 19, 25 and the respective parachutes 22 and 26. The movement of the parachutes and their simultaneous turning movement in opposite

directions, will slacken certain of the wires 65 24 and 29 at one side edge of the aeroplanes and pull upon the opposite wires on each aeroplane, which will rock the aeroplanes correspondingly, thus raising the opposite side edges of the aeroplanes a greater degree and adapting said raised edges to impinge upon the air. 70

As the sets of upwardly-inclined side edges of one set of aeroplanes are driven in an opposite direction from the raised side edges 75 of the aeroplanes forming the other set thereof, the tendency of these oppositely inclined sets of aeroplanes on the respective parachutes 22, 26, is to lift the entire flying machine vertically, and it will be noted that the 80 rate of speed had by the motor 13 will control the degree of turning movement and compression of the torsion springs 21, 27, and of course define the degree of inclination given to the two sets of aeroplanes, 85 which by their impingement upon the air regulate their lifting power.

Having attained a desired height, the aviator can direct the flying machine in any lateral direction by turning the hand wheel 90 18 a proper degree, so as to dispose the weight of the motor and operator at the side that is to be depressed, such depression of the car at one side correspondingly inclining the masts 10, 11, and parachutes 22, 26, thus 95 adapting the aeroplanes on said parachutes to propel the flying machine laterally and upwardly.

When it is desired to descend toward the earth, the hand wheel 18 and eccentric controlled thereby, is adjusted so as to dispose the weight of the motor and aviator normally or in a manner that will give the masts 10, 11, erect positions, then a decrease 100 in speed of the motor will permit the gravity of the apparatus to overcome to a certain degree the lifting power of the aeroplanes, and the parachutes 22, 26 being perforated by the partial opening of the aeroplanes, have just sustaining power sufficient to control the safe descent of the flying machine. 110

It will be noted that when the machine is seated on a level surface, the resilient supporting means provided permits the weight of the parachutes 22, 26, to somewhat compress the torsion springs 21, 27, and consequently rock the aeroplanes into a partly open condition, which will enable said aeroplanes to start the upward movement of the flying machine when the motor 13 is started 115 120 into operation.

Having thus described my invention, I claim as new and desire to secure by Letters Patent:

1. A flying machine comprising a mast, a 125 sleeve slidable thereon, a parachute connected with the sleeve, a fixed support on the mast, a spring arranged between the

sleeve and the support, said parachute having radial openings therein, aeroplanes pivoted in the openings, a connection between said planes and the fixed support for normally holding them in closed position and means for rotating the mast for the purpose set forth.

2. In an apparatus for aerial navigation, the combination with two masts, one rotatable in the other, of a parachute on one mast and having apertures therein, aeroplanes rockably hung in said apertures, and means actuated by a turning and sliding movement of the mast carrying the parachute, for rocking the aeroplanes and graduating the opening and closure of the apertures.

3. In an apparatus for aerial navigation, the combination with two masts, one rotatable in the other, of a parachute carried by each mast, said parachutes having a like number of apertures therein, aeroplanes rockably hung in the apertures in each parachute, and means controlled by the turning 25 of the parachutes on the masts, adapted to rock the aeroplanes in the apertures for opening or closing them.

4. In an apparatus for aerial navigation, the combination with two masts, one rotatable in the other, of apertured parachutes mounted on the masts and having a plurality of apertures in each parachute, an equal number of aeroplanes rockably hung in the apertures in each parachute, means controlled by the rotation of the masts, adapted to rock the aeroplanes, and means adapted for rotating the masts in opposite directions.

5. In an apparatus for aerial navigation, the combination with two masts, one rotatable in the other, and two apertured parachutes mounted on the masts, of aeroplanes rockably hung in the apertures in the parachutes, and torsion springs connected with the aeroplanes and with the masts, the torsion of said springs being adapted for controlling the rocking movement of the aeroplanes.

6. In an apparatus for aerial navigation, the combination with two masts, one rotatable in the other, two apertured parachutes

mounted on the masts and turnable thereon, and aeroplanes rockably hung in the apertures in the parachutes, of a radial flange secured on each mast below and near each parachute, torsion springs connecting each mast with a respective parachute, and connections of wire or the like extended between the aeroplanes and the radial flanges for the control of the rocking movement of the aeroplanes.

7. In an apparatus for aerial navigation, the combination with two masts, one rotatable in the other, two apertured parachutes mounted on the masts and turnable thereon, and aeroplanes rockably hung in the apertures in the parachutes, of a radial flange secured on each mast below and near each parachute, torsion springs connecting each mast with a respective parachute, connections of wire or the like extended between each radial flange and a respective set of aeroplanes for controlling the rocking movement of the aeroplanes, gearing secured on the lower portions of the masts, and a supported motor adapted to rotate the gearing and the masts in opposite directions.

8. In an apparatus for aerial navigation, the combination with two masts, one rotatable in the other, a motor gear connected with the masts for their rotation, and a frame for supporting the motor, of a car carrying the motor support, and an eccentric mechanism mounted in the car and connected with the masts and motor support, which enables a change of position of the masts and motor in the car.

9. In a flying machine, a plurality of masts one of which is rotatable in the other, means for rotating the masts, a car supported by the masts and on which the motor is supported, and means for bodily changing the position of the masts with respect to the car.

In testimony whereof I have signed my name to this specification in the presence of two subscribing witnesses.

FRED LINCOLN GOULD.
